UNITED STATES PATENT OFFICE.

JOHN F. CURREN, OF GRAND RAPIDS, MICHIGAN, ASSIGNOR TO NATIONAL SHEET METAL WORKS, OF GRAND RAPIDS, MICHIGAN, A CORPORATION OF MICHIGAN.

SPRAYING CABINET.

Application filed September 8, 1924. Serial No. 736,420.

This invention relates to a spraying cabinet or booth and is particularly concerned with a novel construction for and method of reclaiming the material sprayed which does not adhere to the object against which it is sprayed and which, heretofore, has fallen to the floor either within or outside of the booth or has been carried by air currents through pipes leading from the booth to an exhaust stack, with a consequent waste of a considerable portion of the material. It is an object and purpose of the present invention to provide a spraying cabinet or booth and equip it with means whereby all or nearly all of the material heretofore wasted may be reclaimed for future use. The invention consists in novel constructions and combinations and arrangements of parts for practically effecting this end as well as many others not at this time specifically stated, but which will appear as understanding of the invention is had from the following description taken in connection with the accompanying drawings, in which,

Fig. 1 is a vertical section through the spraying booth and exhaust stack, parts of the construction being shown in side elevation and broken away to illustrate interior mechanism.

Fig. 2 is a vertical section through the outlet stack and the reclaiming cabinet or chamber in the lower end thereof, the section being taken longitudinally of said cabinet or chamber.

Fig. 3 is a horizontal section through the spraying cabinet at a point above the lateral suction nozzles used with the construction, and

Fig. 4 is a front elevation of the cabinet with a part thereof broken away to show the upper outlet nozzle.

Like reference characters refer to like parts in the different views of the drawings.

The cabinet, in which the spraying of material upon the article to be coated occurs, may be made of sheet metal or other suitable material and includes a back 1, sides 2, top 3 and bottom 4 of rectangular outline, the same being substantially square in outline. The front of the cabinet is open there being, however, a downturned upper lip 5 to the front edge of the top 3 which partially closes the front of the cabinet at its upper side and a shorter upturned lip

6 at the front edge of the bottom 4, this lip, in conjunction with the sides, back and bottom forming a pan in which a fluid, indicated at 7 may be held. A table 8 or other suitable support for the article 9 to be sprayed is located within the cabinet being supported on suitable standards as shown. The article 9 may be anything which is to receive a coating. One place where this spraying booth has been used is in coating refrigerator linings on the inside with suitable porcelain material which is sprayed thereon, the lining with the porcelain thereon being afterward baked in a suitable oven in accordance with the well-known processes of baking porcelain onto sheet metal.

Back of the cabinet 1 is an enclosed reclaiming chamber having front and back vertical sides 10 and 11, a bottom 12, ends 13 and a top 14. A vertical partition 15 extends transversely between the front and back from the bottom a little over half way to the top; and at each side of this partition a sheet metal vane 16 extends from the top downwardly and inwardly toward the partition 15, the lower edges of the vanes 16 extending to a plane below the upper edge of the partition 15, as shown in Fig. 2, there being spaces between the lower edges of the vanes and said partition. A liquid 17 is also held in the reclaiming chamber. When the cabinet or booth is used in covering sheet metal with porcelain the liquid at 7 and 17 is water, this being a solvent of the material used. If varnish or other like material is sprayed upon an article within the cabinet a suitable liquid solvent for such spray material is used instead of water, as is evident.

A vertical stack 18 of sheet metal is supported on and above the reclaiming chamber, the top 14 of such chamber having an opening so as to make communication between the interior of the chamber and the interior of the stack. The lower end of the stack is located between the upper edges of the vanes 16. A pipe 19 is positioned horizontally above the top 3 of the cabinet, at its rear end passing through the front side of the stack 18 and being curved upwardly, as indicated at 19^a, while its front end is curved downwardly, as indicated at 19^b, and joins with a suitable nozzle 20 open at its under side and located within the upper front portion of the spraying cabinet. Intermediate the ends of the pipe 19 a fan 21

squarely against the inner or bottom wall of the said socket. The operator then uses a hammer, striking the outer plug in the direction of the length of the axle whereby the wheel is jarred loose from the axle and the key thereof and may be quickly removed.

Having described the invention what is claimed is—

A device adapted to be used for removing a wheel from an axle upon which it is keyed comprising a body provided at its opposite ends with alined sockets of different sizes, and anvil plugs fitting in the sockets.

In testimony whereof I affix my signature.

CASH A. CLEMONS.

and having its rear end extending through the front side of said stack, a nozzle located in the upper front portion of the cabinet having an open lower side connected with the front end of the third pipe, and means for causing air to be drawn through the nozzle into said pipe and thence pass into the stack, substantially as described.

4. In combination, a cabinet having an open front side and adapted to receive articles therein for spraying the same, suction nozzles located in the cabinet, one at each side thereof and one at the upper front portion thereof, pipes connected to said nozzles, a vertical stack located back of the cabinet and connections for carrying air through

the pipes to said stack combined with means for drawing currents of air through the pipes rearwardly, said nozzles at the sides of the cabinet having inturned ends whereby the openings in the said ends of said nozzles are positioned oppositely to each other, and the upper nozzle having an open lower side, substantially as described. 20

5. In combination the elements defined in combination in claim 7, combined with means for adjustably coupling said nozzles at the sides of the cabinet to their respective pipes for adjustment from front to rear and vice versa. 25

In testimony whereof I affix my signature.
JOHN F. CURREN. 30
